FLUID PUMP

Carl Cornelius Farque, San Antonio, Tex., assignor to Olive S. Petty, San Antonio, Tex.

Application March 9, 1942, Serial No. 434,005

5 Claims. (Cl. 103—175)

This invention relates to fluid pumps, and more particularly to reciprocating pumps of the heavy duty type, commonly employed, for example, as slush pumps in drilling operations. In the illustrated embodiment, the invention is applied to a pump of the type in question, constituting an element of a portable pump unit of moderate size, but it will be understood that the invention, in certain aspects, is equally applicable to pumps of much greater size. Also, pumps embodying the invention may be employed for a variety of uses, but the invention is particularly advantageous in connection with pumps which are subjected to very considerable wear, such as occurs in slush pumps and the like.

It is a general object of the present invention to provide a reciprocating pump of the type in question, having a compact design and rugged construction, while at the same time being capable of assembly and dis-assembly in a speedy and facile manner, whereby the replacement of worn parts is greatly facilitated.

The greatest wear, in pumps of the type in question, occurs in the lining of the pump cylinder, the "swab rubbers" (of the pump piston), and the inlet and outlet valves. In the case of pumps heretofore commonly used, wherein the pump cylinder is cast in block, and provided with a liner, it has been necessary in order to change the cylinder liner or the swab rubbers, to disassemble the structure sufficiently to permit the piston and piston rod to be removed from the cylinder, after which the cylinder liner may be removed by the use of special tools. This operation is time-consuming and tedious, requiring the services of a specially trained mechanic and necessitating shut-down of the pump for a considerable period of time.

Accordingly, it is an object of the present invention to provide a pump structure in which the pump cylinder is a separate unit comprising a sleeve or cylinder, preferably without a separate liner, which can be readily and quickly removed from the assembly and replaced by a new part, without the use of any special tools and in a manner which does not require any special training or experience. It will be understood that when the pump cylinder is thus removed from the assembly, the piston is exposed and worn piston parts may be replaced without difficulty, and without requiring any further disassembly, except as to the parts to be replaced.

Another disadvantage of pumps of the type now commonly used lies in the fact that in order to provide for reversal of the direction of flow through the pump, it has been necessary to provide inlet and outlet chambers on both sides of the pump and corresponding inlet and outlet ports on both sides, iron plugs being inserted in the ports which are not currently in use. In

order to reverse the direction of flow, these plugs must be removed and suitable pipe connections made, but it is frequently found that the plugs have rusted so tightly in the unused ports that it is necessary to remove them by drilling, which is wasteful and time-consuming. Accordingly, it is an object of the present invention to provide a pump assembly in which the inlet and outlet chambers, which also contain the inlet and outlet valves, constitute interchangeable units which may readily be transposed for the purpose of reversing the direction of flow through the pump without requiring changes in the external piping, thus eliminating the auxiliary chambers and ports mentioned above.

It is a further object of the present invention to provide a pump assembly in which the pump cylinder is supported under compression between appropriate header members with the intermediate position of resilient gaskets, whereby any longitudinal movement of the pump cylinder, induced by friction between the piston and cylinder, will take place in the direction of movement of the piston and will serve to effect a tighter seal between that end of the cylinder which is under the higher pressure and the adjacent header, thus serving to prevent leakage.

Other and further objects, features and advantages of the present invention will be apparent to one skilled in the art from the following description taken in connection with the accompanying drawings in which:

Figure 1 is a side elevation of a portable pump unit in accordance with the present invention, the prime mover and power transmission means being shown schematically;

Figure 2 is a sectional view on a line extending through the inlet and outlet chambers of the pump, and header members, on line 2—2 of Figure 4;

Figure 3 is a vertical section on line 3—3 of Figure 2; and

Figure 4 is a transverse section on line 4—4 of Figure 3.

In order to facilitate an understanding of the invention, reference is made to the embodiment thereof shown in the accompanying drawings and detailed descriptive language is employed. It will nevertheless be understood that no limitation of the invention is thereby intended and that various changes and alterations are contemplated such as would ordinarily occur to one skilled in the art to which the invention relates.

Referring to Figure 1, it will be seen that the portable pump unit comprises a suitable base 10 which may comprise a pair of rails connected by suitable cross members, and which carries a source of motive power 11, a transmission 12, connected with the source of motive power through a clutch 13, and a pump assembly indi-

cated generally at 14. The details of the motive power source and the transmission form no part of the present invention, and will not be described.

Referring now to Figures 2, 3 and 4, the pump assembly comprises generally a pump cylinder 15, inlet chamber 16 and outlet chamber 17, supported and interconnected by header members 18 and 19. The latter may be regarded as common cylinder heads for the pump cylinder and the respective inlet and outlet chambers which, in the present embodiment, are cylindrical in form. The headers 18 and 19 provide communication between the pump cylinder 15 and the respective chambers 16 and 17.

A piston 20 (Figures 3 and 4) is mounted for reciprocation within the pump cylinder 15, and is adapted to be reciprocated through the piston rod 21, which extends rearwardly through the header 19 and through a suitable packing 22. The headers 18 and 19 may be supported in any suitable manner upon the base 10. In the present instance the header 18 is supported upon a bracket 23, secured to the base 10 by means of bolts 23', while the header 19 is supported by means extending from the transmission 12. The pump cylinder 15 and chambers 16 and 17 are in turn supported solely by the headers 18 and 19, between which the cylinder and chambers are held under compression by means of bolts 24 (Figures 1 and 4), extending between the respective headers. Gaskets 25, which are preferably retained in suitable annular recesses formed in the respective headers, are interposed between the said headers and the adjacent end edges of the pump cylinder and inlet and outlet chambers. When the bolts 23' and 24 are removed, which can be easily and quickly done, the pump cylinder, the inlet and outlet chambers, and the header 18 may be readily removed from the assembly, there being no other connection between these members.

Referring to Figure 2, it will be seen that the inlet chamber is provided with a port 26 and threaded connection 26', the latter for effecting connection with an external conduit, and the outlet chamber 17 is provided with a similar port 27 and threaded connection 27'. Preferably, the pump of the present invention is of the double-acting type, although the advantages of the invention may obviously be secured in a single-acting pump. In the present embodiment, the inlet chamber is provided at each end with a spring-pressed valve 28 of conventional design and comprising a support having threaded connection with the inner wall of the chamber. Similarly the outlet chamber 17 is provided at each end with a valve 29. It will be understood that the valves 28 can open only to permit fluid to flow from the chamber 16 into one or the other of the headers, while the valves 29 can open only to permit flow from the respective headers into the chamber 17. Upon reciprocation of the piston 20 toward the right in Figure 3, the valve 28 at the left-hand end of inlet chamber 16 will open to permit fluid to flow from the chamber 16 and port 26 into the header 19, while the valve 29 at the right-hand end of the chamber 17 will open to permit fluid to flow from the header 18 into the chamber 17 and out through the port 27. Upon movement of the piston to the left, the opposite valves come into play.

From the foregoing, it will be apparent that in order to replace a worn pump cylinder, or worn piston parts, or to reverse the direction of flow

of the pump, or to replace worn valve parts, all that is necessary is to remove the bolts 23' and 24 and effect the necessary replacements. In order to reverse the direction of flow, the inlet and outlet chambers are detached from the external piping and are simply transposed, the external piping being reconnected without undergoing any change in extent or location.

If desired, a liner may be employed in the pump cylinder 15, in which case the gaskets interposed between the respective ends of said cylinder and the respective headers will be made of sufficient breadth to abut the respective ends of the liner as well as the cylinder casing.

From the foregoing description it will be apparent that the pump of the present invention possesses the several advantages heretofore mentioned and, in addition, is simple, inexpensive, compact, and rugged.

Having thus described the invention, what is claimed as new and desired to be secured by Letters Patent is:

1. A fluid pump comprising a pump cylinder, a piston reciprocable in said cylinder, an inlet chamber, an outlet chamber, said cylinder and chambers constituting separately formed demountable units, detachable means including a pair of header members for supporting said cylinder and chambers in operative relation, at least one of said header members affording communication between said cylinder and said chambers, valves associated with and carried by said respective chambers for controlling the direction of flow between said cylinder and said chambers, each said chamber having a port affording communication between said chamber and an external conduit independently of said header members, and means for reciprocating said piston.

2. A pump according to claim 1, said chambers being interchangeable for reversing the flow through said pump.

3. A fluid pump comprising a pump cylinder, a piston reciprocable in said cylinder, an inlet chamber, an outlet chamber, said cylinder and chambers constituting separately formed demountable units, a pair of header members each supporting and affording communication between adjacent ends of said cylinder and chambers, valves associated with and carried by each said chamber and disposed adjacent the respective ends thereof for controlling the direction of flow between said cylinder and said chambers, each said chamber having a port affording communication between said chamber and an external conduit independently of said header members, means for reciprocating said piston, and readily detachable means accessible exteriorly of the pump for maintaining said cylinder, chambers and header members in assembled relation.

4. A pump according to claim 1, said cylinder and said chambers comprising cylindrical sleeves and being maintained in position by compression between said header members.

5. A pump according to claim 1, said cylinder and said chambers comprising cylindrical sleeves and being maintained in position by compression between said header members, and a resilient gasket interposed between each end of said pump cylinder and the adjacent header member, whereby any axial movement of said cylinder, due to friction exerted thereon by said piston, will increase the pressure between that end of said cylinder which is under the higher pressure and the adjacent gasket.

CARL CORNELIOUS FARQUE.
